UNITED STATES PATENT OFFICE.

JAMES L. BUTLER, OF ALLIANCE, OHIO.

BOTTOM BOARD FOR FOUNDRY-FLASKS.

No. 893,703.

Specification of Letters Patent.

Patented July 21, 1908.

Application filed April 2, 1908. Serial No. 424,763.

To all whom it may concern:

Be it known that I, JAMES L. BUTLER, a citizen of the United States, residing at Alliance, in the county of Stark and State of Ohio, have invented certain new and useful Improvements in Bottom Boards for Foundry-Flasks; and I do hereby declare that the following is a full, clear, and exact description of the same, reference being had to the accompanying drawing, making a part of this specification, and to the numerals and figures of reference marked thereon.

The object of the present invention is to provide a bottom board for foundry flasks that is practically indestructible, and at the same time so formed that it will be light and easy to move about.

Figure 1 is a perspective view. Fig. 2 is an end view. Fig. 3 is a sectional view taken on line 3—3, Fig. 2.

Similar numerals of reference indicate corresponding parts in all the figures of the drawing.

In the accompanying drawing, 1 represents the supporting bars, which are formed of a suitable length to support the board proper. The bars 1 are preferably formed channel shape, and as shown, they are provided with the top and outward extended flanges, 2, and the lower outward extended flanges, 3. It is well understood that bottom boards of this class must be rigid in order to prevent any springing and owing to the fact that they are to be handled from time to time it is of importance that they be light. Heretofore bottom boards of this class have been formed of wood, but owing to the use to which they are put they are easily destroyed or injured by burning and warping.

40 By my peculiar arrangement I am enabled to produce a board that is indestructible and one that will not be injured from use.

For the purpose of providing rigidity the corrugated metal sheet 4 is provided, which 45 corrugated metal sheet is provided with the extended or flange portions 5. Upon the upward extended corrugations of the corrugated sheet 4 is placed the bottom sheet 6, the upper surface of which is designed to receive and hold a foundry flask in the same manner as the common and ordinary wood board support.

The sheet 6 is folded over and upon the upper outward extended flanges 2, to which 55 flanges the sheet 6 is securely attached by suitable rivets 7. The ends of the board or

sheet 6 are folded over and under the extended portions 5 of the corrugated sheet 4 and securely connected thereto by means of suitable rivets 8, by which arrangement the 60 sides and ends of the bottom board are securely connected to the supporting bars, 1, and the corrugated sheet respectively.

For the purpose of preventing any springing movement the plain and smooth sheet 6 65 is riveted or otherwise connected to the upward extended corrugations of the corrugated sheet 4, thereby securely connecting the corrugated sheet 4, and the plain sheet 6 together to produce a light and rigid structure 70 well adapted for the purpose designed.

Having fully described my invention what I claim as new and desire to secure by Letters Patent, is—

1. As an improved article of manufacture, 75 a bottom board for foundry flasks, consisting of supporting bars, a corrugated sheet located between the supporting bars, a sheet located upon the upper corrugations of the corrugated sheet and the sheet resting upon 80 the corrugations of the corrugated sheet secured to the supporting bars, substantially as and for the purpose specified.

2. As an improved article of manufacture, 85 a bottom board for foundry flasks, consisting of supporting bars, a corrugated sheet provided with extended non-corrugated portions, a plain sheet resting upon the upper corrugations of the corrugated sheet, said plain sheet folded upon and secured to the extended non- 90 corrugated portions of the corrugated sheet, substantially as and for the purpose specified.

3. As an improved article of manufacture, 95 a bottom board for foundry flasks, consisting of supporting bars, said supporting bars provided with outward extended flanges, a corrugated sheet provided with non-corrugated extended portions, a plain sheet resting upon the tops of the upper corrugations of the corrugated sheet and the plain sheet folded upon 100 and secured to the outward extended flanges of the supporting bars and the non-corrugated portions of the corrugated sheet respectively, substantially as and for the purpose specified.

4. As an improved article of manufacture, 105 a bottom board for foundry flasks, consisting of supporting bars, said supporting bars provided with outward extended flanges, a corrugated sheet provided with non-corrugated extended portions, a plain sheet resting upon the tops of the upper corrugations 110 of the corrugated sheet and the plain sheet

folded upon and secured to the outward extended flanges of the supporting bars and the non-corrugated portions of the corrugated sheet, respectively, and the plain sheet secured to the upward extended corrugations of the corrugated sheet, substantially as and for the purpose specified.

In testimony that I claim the above, I have hereunto subscribed my name in the presence of two witnesses.

JAMES L. BUTLER.
